UNITED STATES PATENT OFFICE.

CHARLES D. GOLDEN, OF CHICAGO, ILLINOIS.

DESIGN FOR A CLOTHES-RACK.

40,688.

Specification for Design.

Patented May 10, 1910.

Application filed February 5, 1910. Serial No. 542,332. Term of patent 3½ years.

To all whom it may concern:

Be it known that I, CHARLES D. GOLDEN, a citizen of the United States, residing at Chicago, county of Cook, and State of Illinois, have invented a new, original, and ornamental Design for a Clothes-Rack, of which the following is a specification, reference being had to the accompanying drawing, forming a part thereof.

The drawing is a front view of a clothes rack, showing my new design.

I claim:

The ornamental design for a clothes rack, as shown.

CHAS. D. GOLDEN.
